UNITED STATES PATENT OFFICE.

THOMAS J. CRILLY AND FREDERICK M. WILSON, OF DENVER, COLORADO,

FUEL-IGNITER.

1,150,177.

Specification of Letters Patent. Patented Aug. 17, 1915.

Application filed June 11, 1914. Serial No. 844,481.

To all whom it may concern:

Be it known that we, THOMAS J. CRILLY and FREDERICK M. WILSON, citizens of the United States, residing in the city and county of Denver and State of Colorado, have invented certain new and useful Improvements in Fuel-Igniters; and we do declare the following to be a full, clear, and exact description of the invention, such as will enable others skilled in the art to which it appertains to make and use the same, reference being had to the accompanying drawings, and to the characters of reference marked thereon, which form a part of this specification.

Our invention relates to improvements in fuel igniting devices, our object being to provide a device of this character which shall be exceedingly simple in construction and efficient in use.

Our further object is to provide a device adapted to carry an absorbent substance which may be saturated with a combustible liquid which will gasify under the influence of heat, whereby a device of comparatively small bulk will hold a sufficient quantity of liquid to burn a relatively long time, thus making it practicable for igniting either wood, coal or other fuel.

Our further object is to provide a device of this character which will obviate the necessity of using kindling wood in building coal and hard-wood fires.

To be more specific, the device consists of a perforated circular member of suitable width located and clamped between the upper and lower disks forming heads, the two disks projecting circumferentially beyond the perforated body member far enough to permit their connection by means of bolts which are passed through openings formed in the circumferentially projected portions of the disks, the shanks of the bolts being located outside of the perforated body member and secured in place by nuts applied to the protruding lower extremities of the bolts. The body member may be formed by riveting the overlapping extremities of a piece of sheet metal of suitable thickness to form a relatively durable device. A handle is connected with the body of the device by the same rivets or other fastening devices that connect the overlapping extremities of the body-forming plate. The hollow structure thus formed contains a quantity of non-combustible absorbent material, as asbestos,

which may be packed therein in proper quantity. It should not be packed so tight as to materially interfere with its absorption of the liquid, as coal oil or gasoline, which is to be used with the device, and in which the latter may be immersed for charging purposes.

Having briefly outlined our improved construction, we will proceed to describe the same in detail, reference being made to the accompanying drawing, in which is illustrated an embodiment thereof.

In this drawing, —Figure 1 is a top plan view of the device. Fig. 2 is a side elevation of the same. Fig. 3 is a central vertical section of the same taken on the line 3—3, Fig. 1. Fig. 4 is a top plan view with the upper head or disk removed.

The same reference characters indicate the same parts in all the views.

Let the numeral 5 designate the body of the device, which is perforated as shown at 6. As illustrated in the drawing, this body part is formed by bending a piece of sheet metal into circular shape and overlapping its extremities, as shown at 7, these overlapped extremities being connected by rivets 8 or other suitable fastening devices. These rivets also preferably pass through an interiorly located part 9 of a handle 10, the part 9 being bent as shown at 12, at right angles to the body 13 of the handle. The body member is secured between upper and lower disks 14 and 15, the disk 14 forming the top or upper head and the disk 15 the lower or bottom head of the device. The chamber inclosed by the member 5 and the two heads, is filled with a quantity of non-combustible absorbent material 16, which may be composed of asbestos or other suitable or similar material which is sufficiently absorbent for the purpose and which at the same time, will not be destroyed by the heat incident to the use of a device of this character. The disks 14 and 15 extend circumferentially, as shown at 17 and 18, beyond the body of the device and are provided with openings 19 and 20 through which bolts 21 are passed. The lower extremities of these bolts extend beyond the body of the disk and are threaded as shown at 22, to receive fastening nuts 23, the shanks of the bolts between the disks being located outside of the body member 5 but preferably in contact therewith.

It is evident that any desired number of

perforations 6 may be employed, according to the rapidity with which it is desired to burn the liquid contents of the absorbent portion of the device. As illustrated in the drawing, we have shown a central opening 24 in the bottom disk 15, which may be utilized for draft purposes during the use of the article in the regular performance of its function. It is assumed that when in use it will rest upon the lower protruding extremities of the bolts 21, whereby it will be supported a short distance above the adjacent supporting surface. This will give an opening for the air to pass underneath and enter the chamber in the body of the device and pass up through the absorbent material and thus facilitate the combustion of the liquid contents of the substance 16, which contents will be gasified and when ignited, will produce jets of flame which will lead from each perforation 6 of the body of the device. These jets of flame will extend outwardly and upwardly, and serve to ignite the fuel in a manner that will be readily understood. The device is made of such size, and therefore, of such igniting capacity that it will properly perform the required function.

It is evident that the article may be made of any suitable size without in any way departing from the spirit of the invention.

Having thus described our invention, what we claim is,

1. A fuel igniting device composed of a perforated body member, two plates between which the body member is secured, and a quantity of non-combustible absorbent material located within the chamber thereby formed.

2. A fuel igniting device composed of a circular perforated body member, two plates

between which the body member is clamped, a quantity of non-combustible absorbent material located within the chamber thereby formed, and a handle suitably connected with the body member. 45

3. A fuel igniting device comprising a circular perforated metal member, top and bottom disks applied thereto and between which the body member is clamped, a quantity of non-combustible absorbent material being located within the chamber thus formed, the lower plate of the device having a draft opening, and a handle of suitable length connected with the body of the instrument to facilitate its manipulation. 50 55

4. A fuel igniting device comprising a perforated circular body member composed of a plate of sheet metal whose free extremities are overlapped and secured together by suitable fastening devices, a handle member having a part bent to engage the overlapped extremities of the body member and connected with the latter by the same fastening devices which secure the overlapping extremities of the same, top and bottom disks applied to the body member and projecting circumferentially beyond the latter, the projecting portions having openings, and fastening bolts passed through the last named openings and secured by nuts, the shanks of the bolts being located outside of the interposed body member, substantially as described. 60 65 70

In testimony whereof we affix our signatures in presence of two witnesses.

THOMAS J. CRILLY.
FREDERICK M. WILSON.
